UNITED STATES PATENT OFFICE

151,059

DESIGN FOR A CAMERA COVER

Charles E. Main, Rochester, N. Y., assignor to Eastman Kodak Company, Rochester, N. Y., a corporation of New Jersey

Application October 4, 1946, Serial No. 133,768

Term of patent 14 years

(Cl. D61—1)

To all whom it may concern:

Be it known that I, Charles E. Main, a citizen of the United States, residing at Rochester, in the county of Monroe and State of New York, have invented a new, original, and ornamental Design for Camera Cover, of which the following is a specification, reference being had to the accompanying drawings, forming a part thereof in which:

Fig. 1 is a perspective view taken from the top and rear and showing my new design.

Fig. 2 is a perspective view taken from the top and front, showing my new design.

Fig. 3 is a side elevation of the camera cover shown in the preceding figures.

I claim:

The ornamental design for camera cover, as shown.

CHARLES E. MAIN.
